(57) **CLAIM**

The ornamental design for a pill box, as shown and described.

DESCRIPTION

FIG. 1 is a top perspective view of a pill box showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detailed view of Area 9 circumscribed within FIG. 2; and,

FIG. 10 is an enlarged detailed view of Area 10 circumscribed within FIG. 8.

The broken lines depict portions of the article and environment that form no part of the claimed design.

1 Claim, 10 Drawing Sheets
